ATTYS.

UNITED STATES PATENT OFFICE.

SIMON MYERSON, OF CAMBRIDGE, MASSACHUSETTS.

ARTIFICIAL TOOTH.

1,243,335.

Specification of Letters Patent. Patented Oct. 16, 1917.

Application filed June 8, 1917. Serial No. 173,519.

To all whom it may concern:

Be it known that I, SIMON MYERSON, a citizen of the United States, residing at Cambridge, in the county of Middlesex and 5 State of Massachusetts, have invented new and useful Improvements in Artificial Teeth, of which the following is a specification.

The principal object of this invention is to provide a replaceable tooth body for posterior teeth, and a backing therefor, said body and backing being formed to constitute a tooth of such strength as to obviate the necessity of boxing and to effectively resist all forces tending to displace the body 15 relatively to the backing, and to increase the length of attachment between the pivot and its socket.

Hitherto all bicuspid and molar tooth bodies intended for use with metal supports 20 and dependent on pivots or tenons for attachment of the body to the backing, have been so constructed as to necessitate what is known as boxing by the dentist, to secure good results. This boxing is objectionable, 25 because it prevents accurate and simple replaceability. Moreover, the location of the pivot or tenon has heretofore been such as to weaken the tooth in its most vital part, viz., the occlusal portion.

To overcome these and other disadvantages, I have constructed a posterior tooth body and a metal backing therefor carrying a pivot or tenon, all embodying the improvements which I will now proceed to 30 describe and claim.

Of the accompanying drawings forming a part of this specification,—

Figure 1 is a perspective view of a tooth body constructed in accordance with my invention.

Fig. 2 is a section on line 2—2 of Fig. 1.

Fig. 3 is a perspective view of the metal backing.

Fig. 4 is a sectional view showing the 45 body and backing assembled.

Fig. 5 is a section on line 5—5 of Fig. 4, and an elevation of the parts at the right of said line.

Fig. 6 is a sectional view showing certain 50 structural changes.

Fig. 7 is a sectional view showing other structural changes.

Fig. 8 is a perspective view of the backing and pivot or tenon shown by Fig. 7.

55 The same reference characters indicate the same parts in all the figures.

In Figs. 1 to 6, inclusive, 12 represents a porcelain tooth body comprising a base or buccal portion having a flat lingual face 13, and an inclined ridge lap 15, and an occlusal portion 14 provided with the buccal and lingual cusps, the occlusal portion and ridge lap being at opposite ends of the lingual face. The lingual face 13 is hereafter referred to as a backing-engaging face, and 60 the occlusal portion 14 has an inwardly projecting extension on which the lingual cusp is formed. Said extension has another backing-engaging face 16, projecting rearwardly from the inner end of the lingual 65 face 13 and arranged at an angle therewith, the angle formed by said faces being preferably obtuse, as shown by the drawings, although it may be a right or other angle, if desired. I have hereinafter called the 70 face 16 a back, because it forms the back of that part of the body which has the lingual cusp. The buccal portion is formed on that part of the body which has the buccal cusp.

The body 12 is provided with a socket 80 which includes an elongated cavity 17, having a closed or continuously walled inner portion located within the occlusal portion 14, the closed inner end of said cavity being suitably spaced from the acting surface of 85 the occlusal portion, as shown by Fig. 2. The outer end of said cavity constitutes an end-mouth opening on the ridge lap. The socket also includes a lateral mouth or portion 17^a opening on the lingual face 13 and 90 having sides of substantial width.

The metal backing shown detached by Fig. 3, is of angular form, and includes a wing 18 formed to fit the lingual face 13 and provided with a pivot or tenon including a body portion 19 which is complementary to the cavity 17, and a neck portion 19^a complementary to and occupying the lateral socket mouth 17^a, said neck having sides of 95 substantial width bearing on the sides of the mouth 17^a. The portion of the socket having the lateral mouth is preferably key-hole shaped in cross section, the corresponding portion of the tenon being similarly formed. The metal backing also includes a wing 20, 100 arranged at an angle with the wing 18 and formed to fit the rearwardly projecting face 16 of the occlusal portion. The sides of the mouth 17^a and neck 19^a form reciprocal bearing surfaces resisting strains tending to spring the body on the tenon. 105 The wing 20 and the back 16 are prefer-

ably curved, as clearly shown by Figs. 1, 3 and 5, the back 16 having a reentrant curve, such as may be conveniently formed by a rotary cylindrical grind stone, while the inner 5 side of the wing 20 presents a salient curve. The interengagement of said curved back and wing resists strains tending to swing the body 12 on the tenon 19, so that the wing 18 and the tenon neck 19^a are relieved 10 of much of the duty of resisting such strains. The tenon may be parallel with the wing 18, as shown by Figs. 1 and 4, or may be inclined relatively to said wing, as shown by Fig. 6.

15 The inner end of the neck 19^a and the corresponding end of the socket mouth may be inclined, as shown at 21, Fig. 6, to increase the area of the complementary bearing faces of said neck and mouth, and the said socket 20 mouth and neck may be extended, as shown, to cause a portion of the socket mouth to open on the back 16, and to cause a portion of the neck to join the wing 20.

The tenon and socket may have any desired form in cross section, and they may be tapered, as shown by Figs. 2, 3 and 4, or formed without a taper, as shown by Fig. 6.

The described construction of the body and backing enables the body to be securely 30 supported by the backing without boxing, so that the greatest degree of interchangeability is maintained. As shown by Fig. 7, the ridge lap may be omitted, the backing-engaging lingual face 13^a being extended to intersect the anterior or buccal face of the tooth body. In this embodiment 35 of the invention both the end mouth and the lateral mouth of the socket open on the lingual face.

40 The backing is composed of a wing 20 fitting the back 16, and a lingual wing 18^a covering the lingual face and carrying a pivot or tenon 19^b which is joined directly to the inner side of said wing and is connected with a portion thereof by a relatively short neck 19^c, as shown by Fig. 8. Said neck occupies a corresponding socket mouth formed in the lingual face 13^a. The lingual wing 18^a covers the end mouth of the 50 socket and any crevice that may exist at said end mouth in consequence of an imperfect fit of the tenon therein.

In each embodiment of the invention the wing 20 fitting and supporting the back 55 16, is adapted to reinforce that part of the occlusal portion which has the back 16, and resist forces of mastication tending to strain and break the occlusal portion. The words "of substantial width" describing the sides 60 of the socket mouth and of the tenon neck, are employed to convey the idea that these sides constitute reciprocal bearing surfaces adapted to resist strains tending to swing the tooth body on the tenon, and to distinguish the sides of the neck from acute an-

gled edges such as would be provided if the cylindrical body portion 19 of the tenon were soldered directly to the backing.

I claim:

1. An artificial tooth comprising a body 70 composed of a buccal portion having a backing-engaging lingual face, and an occlusal portion including an extension projecting inwardly from the buccal portion, said occlusal portion having buccal and lingual cusps and a backing-engaging extension face angularly arranged relatively to said lingual face, said body having a socket 75 extending longitudinally through the buccal portion into the occlusal portion and opening on said lingual face, and an angular backing formed to fit said lingual and extension faces, and having a tenon complementary to said socket.

2. An artificial tooth comprising a body 80 composed of a buccal portion having a backing-engaging lingual face, and an occlusal portion, including an extension projecting inwardly from the buccal portion, said occlusal portion having buccal and lingual cusps and a backing-engaging extension face angularly arranged relatively to said lingual face, said body having a socket 85 extending longitudinally through the buccal portion into the occlusal portion and opening on said lingual face, and an angular backing formed to fit said lingual and extension faces, and having a tenon complementary to said socket, the said extension face and the portion of the backing engaged 90 therewith having complementary opposed surfaces one of which is reentrant and the other salient whereby strains tending to swing the body on the backing are resisted.

3. An artificial tooth comprising a body 105 composed of a buccal portion having a backing-engaging lingual face, and an occlusal portion including an extension projecting inwardly from the buccal portion, said occlusal portion having buccal and lingual cusps and a backing-engaging extension face angularly arranged relatively to said lingual face, said body having a socket 110 extending longitudinally through the buccal portion into the occlusal portion and including a mouth opening on said lingual face and on a part of said extension face, and an angular backing formed to fit said lingual and extension faces and having a tenon complementary to said socket and including a neck formed to occupy the entire 115 socket mouth including the part thereof which opens on said extension face.

4. An artificial tooth comprising a body having a buccal face, a backing-engaging 125 lingual face which intersects the buccal face, and a socket including an elongated cavity inclined relatively to said lingual face and having end and lateral mouths each opening on the lingual face, and a backing formed 130

to cover said lingual face and the socket mouths therein, and provided with a tenon complementary to said socket and including a body portion and a neck both joined to the inner side of said backing.

5. An artificial tooth comprising a body having a buccal face, a backing-engaging lingual face which intersects the buccal face, an occlusal portion including an extension 10 projecting inwardly from the buccal portion, said occlusal portion having buccal and lingual cusps, a backing-engaging tension face angularly arranged relatively

to said lingual face, and a socket including an elongated cavity inclined relatively to 15 said lingual face and having end and lateral mouths opening on the lingual face, and a backing formed to fit and cover said faces and the socket mouths in the lingual face, and provided with a tenon complementary to 20 said socket and including a body portion and a neck both joined to the inner side of said backing.

In testimony whereof I have affixed my signature.

SIMON MYERSON.
